UNITED STATES PATENT OFFICE

MATVEY A. CAPELIUSCHNICOFF, OF NEW YORK, N. Y.

DRILLING TOOL

Application filed January 12, 1931. Serial No. 508,064.

My invention relates to well drilling tools and has a particular reference to tools or bits employing rotary cutters and especially adapted for a rotary drilling.

5   Rotary cutters such as disc cutters, rock cutters, etc., have proven very successful for drilling through more or less hard formations. Their action, however, depends on direct pressure from their drilling pipe as the 10 rotation is caused by frictional contact with the well bore bottom as they are rolled around by the rotating pipe. In the usual construction, such discs are mounted on short shafts (horizontal or inclined) and rotate freely on 15 these shafts, and are not mechanically connected with the power transmitting shaft (or pipe). The force required for drilling action is produced by direct pressure at the points of contact of the discs with the earth formations in the well. The result of such pressure 20 is that when the tool meets inclined hard strata it has a tendency to deviate from the straight vertical direction, gradually following the direction of inclination of the 25 rock formations. This causes crooked holes (wells) peculiar to rotary drilling, the total deviation being often quite large for deep wells, and the bending of the drill pipe often causing excessive friction. The excessive 30 pressure also tends to cause a rapid wear of the pivots or shafts supporting the rotating discs.

In order to eliminate these difficulties I provide a tool in which the cutting discs receive 35 their rotating torque from the main driving (rotating) shaft or pipe, being connected with same through a suitable gearing, fully enclosed and running in oil, with bearings also enclosed and running in oil. With 40 this arrangement the pressure may be quite light as the rotating torque of the cutters does not depend on this pressure. The tool has a true milling action on the strata, with a result that the hole is obtained much more 45 nearly straight than it would be possible with any other form of rotary tools.

Since the weight of the drilling string is not required to produce the rotating torque, it is possible with my arrangement to use a 50 rotating motor of a low power and which

can be placed at the bottom of a well near the drilling bit.

Any suitable motor can be used for this purpose, such as an electric, hydraulic, or a compressed air motor, etc., but my tool is especially adapted to be used with my hydraulic rotary motors described in my U. S. Patents Nos. 1,681,094 and 1,785,727. These patents describe a construction with stationary pipes and a motor at the bottom end of the pipes directly operating a drilling cutter through a geared transmission. My drilling tool forming a subject matter of this application can be attached to the stationary portion of the motor housing, and the rotating portion connected with the operating spindle. The gearing interposed between the stationary and rotating portions will cause the positive rotation of the cutting discs by the motor while the main shaft or stem of the tool is rotated directly by this motor.

An additional advantage of my arrangement is also that it permits the bearings and the journaled portions of shafts to be fully enclosed so as to retain their lubricants and 75 to protect them from dirt, water, etc.

My invention is more fully described in the accompanying specification and drawings in which:—

Fig. 1 is a sectional elevation of my tool, 80 Fig. 2 is a sectional view taken on the line 2—2 of Fig. 1, Fig. 3 is a sectional elevation of a modified construction, Fig. 4 is a sectional view taken on the line 4—4 of Fig. 3 and Fig. 5 is a sectional elevation of my tool 85 assembled with my hydraulic motor described in my above specified patents.

My tools consists of a tubular housing 1 screwed on one end of a connecting piece or reducer 2 the other and larger end of which 90 is screwed on the end of a stationary pipe 3 representing an outer shell of my rotary motor described in the above patents. The reducer 2 has a packing 4 tightened with a gland nut 5 against a shoulder 6 and forming a bearing for a tubular stem 7 the upper end of which is attached to the drilling spindle 7' by a nut 9.

The spindle 7' extends from a planetary transmission 10 connected at the other end 100

with a hydraulic motor 11. The tubular housing 3 is attached at the upper end to a drill pipe 12 by means of a reducer 13.

A shoulder 49 is located near the lower end of the stem 7. A bushing 14 with a bevel gear 15 is pressed against the shoulder 49. A key 16 prevents the rotation of the gear on the stem. The gear is clamped in its place by a nut 17 on the threaded end of the stem, through a sleeve 18. A bushing 19 is rotatively supported in the sleeve 18 by means of packing rings 20 and a gland nut 21. The bushing 19 is permanently screwed into an outer shell 22 the upper end of which is rotatively supported on the housing 1 with packing rings 23 between them clamped by a nut 24.

A ring 25 is screwed into the lower end of the housing 1, with a shoulder 26 supporting the packing 23, and with a bevel gear 27 at its lower edge. The housing 1 supports a roller bearing 28 the inner race of which is mounted on an inner shell 29 pressed on the shank 7 with a key 30. The lower end of the inner shell 29 has apertures 31 in which round nuts 32 are journaled screwed on the ends of shafts 33. These shafts support bevel pinions or satellites 34 in mesh with the gears 15 and 27. The middle portion of each shaft is journaled in bosses 35 on the sides of the outer shell 22 with packing rings 36 and gland nuts 37. Thrust ball bearings 38 are interposed between the pinions 34 and shoulders 39 in the bosses 35. The outer ends of the shafts are provided with heads 40 fitting in corresponding recesses of disc cutters 41 which are pressed and keyed on the shafts 33, with keys 42. The shafts are placed at an angle with the horizontal line in order to bring the lower edges of the cutters close together. This arrangement permits the cutters to remove practically all the material at the bottom of a hole (well).

All of the bearings and frictional surfaces of my device, as can be seen from the drawings, are fully enclosed with packing glands and can retain their lubrication, practically, indefinitely, being also fully protected from water, dirt, etc.

The operation of my device is as follows. The hydraulic motor in the shell 3, Fig. 5 is assembled with my drilling tool and is mounted on the end of the drilling pipe 12 to be lowered into the well. The ordinary mud solution is then pumped through the drilling pipe. It passes through the rotor 11 of the hydraulic motor thereby causing same to rotate, and flows in the channels around the transmission housing into the hollow stem 7, emerging at the bottom to spread around the cutting edges of the disc cutters 41.

The motor turns the spindle 7 through the planetary transmission 10. The gear 15 rotates with the spindle, rolling the satellites

84 over the stationary gear 27. As a result, the shafts 33 with the cutting discs 41 will turn on their axes, the periphery of the disc acting like a rotary knife in cutting the earth formations through which the hole is being drilled. At the same time the outer shell 22 with the shafts 33 and discs 41 will slowly rotate around the axis of the stem 7 thereby distributing the cutting operation uniformly throughout the exposed area of the earth formation, the drilling being also assisted by the tangential pressure on the advancing cutting edges of the discs.

The drilling action, therefore, consists of two positive operations, both produced by the drilling motor: first, rotation of the discs themselves which act as rotary knives, and, second, the rotation of the discs around the axis of the tool or, which is the same thing, around the axis of the well.

The construction of my device is such that all the rubbing or frictional surfaces, bearings, gears etc., are totally enclosed and sealed with packing glands, so that they retain their lubrication and are fully protected from the mud solution, water and dirt in the well.

A modified arrangement is shown in Figs. 3 and 4. Here the outer shell 43 is rigidly mounted on the stem 7 through an intermediate bushing 44 with a key 45. The inner ends of the shafts 33 are journaled in an inner shell 46. The shafts with the cutters 47 are directly rotated by the stem 7 with their outer and inner shells 43 and 46. The rotation of the cutters on their axes is accomplished by the arrangement of a stationary gear 27 in mesh with the pinions 34 which roll on this gear while rotating around the axis of the tool.

The cutters 47 may have teeth on their peripheries in order to facilitate cutting through hard formations. These cutters may be, of course, of any ordinary shape and design, suitable for different practical conditions.

The positive rotation of the cutting discs enables my tool to exert cutting action quite independently of the axial pressure on the tool, so that a comparatively low powered motor will successfully operate this device. Different gearing arrangement may be used for different drilling conditions, so as to increase either their rotative speed around their axis or their speed of rotation around the axis of the central stem.

My tool is especially suitable for use with my hydraulic drilling device as described in my above mentioned patents. The stationary housing or shell is attached to the stationary portion of the drilling device which in turn is attached to the stationary drill pipe. These parts are defined as "stationary" in a sense that they do not rotate, although, of course, they are gradually lowered into the well as the drilling operation pro-

gresses, and they are differentiated thereby from the rotating portions of the drilling outfit which are directly connected with the operating stem of my tool.

5 I claim as my invention:

1. In a well drilling tool, the combination with a central stem adapted to be rotated by a motor, of a stationary shell rotatively supporting said stem, an outer shell rotatively

10 mounted on said stationary shell, said outer shell being adapted to be rotated by said stem, disc cutters rotatively mounted on said outer shell, and means actuated by said stem to rotate said disc cutters about their axes.

15 2. In a well drilling tool, the combination with a central stem adapted to be rotated by a motor, of a stationary shell rotatively supporting said stem, an outer shell rotatively supported on said stationary shell, said outer shell being adapted to be rotated by said stem, a gear on said stationary shell, shafts rotatively supported in said outer shell, cutting discs on said shafts, and pinions on said shafts in mesh with said gear, said pinions being adapted to cause the rotation of said shafts with said cutters about their axes when said outer shell is rotated by said stem.

20 3. In a well drilling tool, the combination with a stem adapted to be rotated by a motor, of a stationary shell rotatively supporting said stem, an outer shell rotatively supported on said stationary shell, a gear on said stationary shell, shafts rotatively supported in said outer shell, cutting discs on said shafts, pinions on said shafts in mesh with said gear, and a second gear fixedly mounted on said stem and in mesh with said pinions, said second gear being adapted to rotate said pinions and to roll them over said

25 40 stationary gear.

4. In a well drilling tool, the combination with a central stem adapted to be rotated by a motor, of a stationary shell rotatively mounting said stem, an outer shell rotatively supported on said stationary shell and attached to said stem, a gear on said stationary shell, shafts rotatively supported in said outer shell in a radial direction from said stem, cutting discs on said shafts, pinions on said shafts in mesh with said gear, and an inner shell rotatively supporting the inner ends of said shafts and rotatively supported in said stationary shell.

55 In testimony whereof I affix my signature.
MATVEY A. CAPELIUSCHNICOFF.
